of Illinois

Application April 22, 1935, Serial No. 17,628

32 Claims. (Cl. 93—2)

This invention relates to wrapping machines, and particularly to machines for wrapping articles. More specifically the invention relates to a machine for placing and sealing a wrapper about a package.

An important object of the invention is to provide a machine which has new and novel means for feeding a wrapper web and a tape web simultaneously to feeding position, the said mechanism feeding the tape at a more rapid speed than the wrapper so as to provide an opening tab; which has new and novel means for advancing and positioning the article to wrapping position; which has new and improved means for folding and sealing the wrapper; which is provided with novel detector means to prevent feeding of the web when an article is not present; and which is provided with means for delivering the finished wrapped package from the machine.

Another object of the invention is to provide feeding mechanism for a machine of the type described whereby a wrapper web and a tape web is fed in correlated relationship, the tape being fed at a rate of speed different than the wrapper whereby the wrapper, when arranged about the article or package will have a tab projecting therefrom whereby to provide a tab to permit easy opening of the enclosing wrapper.

Another object is to provide package advancing and transfer means for arranging the packages to be wrapped in proper position with respect to the taped wrapper and with respect to the wrapper folding mechanism.

A further object of the invention is to provide means for fastening the tape to the wrapper, means for sealing the wrapper along its longitudinal edges, and means for sealing the ends of the wrapper.

A still further object of the invention is to provide detector means to prevent feeding of the tape or wrapper when an article or package to be wrapped is not present.

Still another object of the invention is to provide a plurality and combination of parts synchronized and correlated with respect to the operation thereof so as to cause operation of certain elements at predetermined times whereby all the parts will operate harmoniously and intermittently in a predetermined sequence.

Another object of the invention is to provide new and improved means operating in timed relationship with the moving and wrapping mechanism for delivering the completely wrapped packages from the machine.

Still another object of the invention is to pro-

vide new and improved clutch mechanism adapted to be controlled by the detector mechanism for controlling the operation of the tape and wrapper feeding mechanism.

Another object is the method of wrapping a wrapper and an enclosed opening strip about a package in a predetermined sequence and in a particular manner.

A still further object of the invention is to provide rotary mounted intermeshing folder mechanism for folding the wrapper about the ends of the package.

Numerous other objects and advantages will be apparent throughout the progress of the following specification.

The accompanying drawings illustrate selected embodiments of the invention and the views therein are as follows:

Fig. 40 is a detail sectional view on the line 40-40 of Fig. 39.

Fig. 41 is a detail sectional view on the line 41-41 of Fig. 39.

Fig. 42 is a detail plan section on the line 42-42 of Fig. 39.

Fig. 43 is a detail vertical view of a modified form of folder, being rotary in operation.

Fig. 44 is a view similar to Fig. 43, the parts being advanced.

Fig. 45 is a detail sectional view on the line 45-45 of Fig. 44.

Fig. 46 is a detail sectional view on the line 46-46 of Fig. 44.

Fig. 47 is a detail plan view of another arrangement of the detector mechanism and is the selected and preferred arrangement to be used with the present machine.

Fig. 48 is a view similar to Fig. 47 with the parts shown in a different position.

Fig. 49 is a detail sectional view on the line 49-49 of Fig. 47.

The invention comprises in general a machine for wrapping regenerated cellulose, paper, or similar wrapping about a carton or package, there

being a tape wrapped within the wrapper and having an end extending from the edge of the wrapper a predetermined distance to provide an opening tab. Both the wrapper and the tape are formed from a continuous web and fed at predetermined rates of speed so that the length of the tape fed will be longer than the wrapper so as to provide an extending tab. Cutting members operate in timed relationship with the feeding mechanism to simultaneously cut the tape and wrapper. During the feeding operation of the wrapper a predetermined amount of adhesive substance is applied thereto in a predetermined position whereby the tape may become fastened to the wrapper. Articles arranged in a carton or package are fed in a predetermined position with respect to the cut wrapper and cooperating tape so that during continued movement of the package, a wrapper will be formed about the package or carton. During the movement of the package throughout its course of movement through the machine, certain folding mechanism folds the wrapper about the carton or package, while other adhesive material applied to the wrapper seals the longitudinal edges of the wrapper as well as the ends thereof. Detector mechanism operating in timed relationship is provided to prevent the feeding of webs and the cutting of wrappers therefrom when a package is not in a proper predetermined position relative to the finder or locating elements of the detector mechanism. Delivery mechanism is provided at the extreme end of the machine and also operates in timed relationship with other mechanism of the machine so as to receive and deliver the wrapped, sealed packages to a predetermined support.

The particular wrapping machine herein illustrated for the purpose of explaining the invention comprises a suitable frame or supporting structure 1. A transverse shaft 2, driven in any suitable manner, such as by an electric motor, not shown, is mounted in suitable bearings 3 and 4, Figs. 1-3. The main drive shaft 2 drives a sprocket 5, Fig. 2, and a sprocket chain 6, driven by the sprocket 5, drives a sprocket 7 which is mounted on a shaft 8 made in two parts 9 and 10 co-extensive with each other as more clearly shown in Fig. 39. A wrapper feed roll 11 mounted on a rotary shaft 12 is driven from the end 10 of the shaft 8 by means of gears 13 and 14, Figs. 1 and 6. A tape feed roll 15 mounted on a shaft 16 is driven from the end 10 of the shaft 8 by gears 17 and 18, Figs. 1 and 6.

Wrapper and tape feed and cutting mechanism

A continuous web of wrapping material 19 is fed from a roll 20 mounted on a shaft 21. The shaft 21 is operatively supported by a bracket 22 rigidly fastened to the top of the frame 1. The wrapper 19 passes about a booster roll 23 and over an idler roller 24 and then between the rollers 11 and 25, the roller 25 being driven by the shaft 12 by means of the gears 26 and 27, Figs. 4 and 5. The feed rollers 11 and 25 feed the wrapper 19 over a guide 28, Fig. 1, to a position between the cutters 29 and 30. The cutter 29 is mounted on the end 10 of the shaft 8 which shaft carries a gear 32 which meshes with a gear 31 on the cutter roller shaft 23, Figs. 4 and 5. The feed rollers 11 and 25 driven by the gears 13, 14, 27 and 26 from the end 10 of the shaft 8 feed the wrapper 19 at a predetermined rate to a position between the cutters 29 and 30.

Tape 34, Fig. 1, from a roll 35 passes over a

booster roller 36 and between the tape feed rollers 15 and 37, Figs. 4 and 5. The feed roller 15 on shaft 16, Figs. 5 and 6, is driven from the end 18 of the shaft 8 through the intermediary of the gears 17 and 18, Fig. 6. The feed roller 37 is driven by the shaft 16 through the intermediary of the gears 38 and 39, Figs. 4 and 5. The tape feed rollers are designed to feed tape to the cutters 29 and 30 at a rate faster than the feeding rate of the wrapper so that a predetermined amount of tape will extend beyond the lower leading edge of the wrapper.

The wrapper 19, Fig. 1, passes between a bar 40, intermittently operated by a cam actuated arm 41 and an adhesive roller 42, the wrapper coming in contact with the adhesive roller 42 intermittently upon operation of the arm 41. The roller 42 which is relatively narrow, Fig. 4, obtains the adhesive from an adhesive receptacle 43 and deposits a spot of adhesive upon the wrapper in predetermined position at each reciprocation of the arm 41. After the predetermined amounts of wrapper and tape have been fed, they are cut by the cutters 29 and 30. The severed wrapper and tape then pass between the guides 44 and 45 and between the rollers 46 and 47. The roller 46 is a rigid revolvably driven roller and drives the companion roller 47. As the tape is fed faster than the wrapper and inasmuch as the tape and wrapper are severed simultaneously, the tape will extend beyond the lower or leading edge of the wrapper and is received between the rollers 46 and 47 before the wrapper is so received. As the tape and wrapper pass between the rollers 46 and 47 and inasmuch as the tape is juxtaposed with respect to the adhesive from the wrapper, the tape will be fastened to the wrapper, there always being a projecting edge in the form of a tab extending from the lower leading edge of the wrapper. The rollers 46 and 47 feed the wrapper with the tab adhered thereto into proper position to become engaged by the on-coming article or package to be wrapped, the wrapper being arranged and supported in the guide member to a position designated generally by the numeral 48.

Package feeding mechanism

The articles or packages to be wrapped are placed on a continuously moving conveyor 51 which is in the form of an endless belt operating between guides, Figs. 1 and 7, from a point forwardly of the wrapper support 48, to the left, Fig. 1. An abutment 52, Fig. 7, in the form of a bar extending across the open end of the conveyor stops the first package 50, Fig. 7, on its movement to the right where an intermittently operated pusher 53 pushes the package 50 from its stationary position on the conveyor 51 to a receiving plate or platform 54. The pusher 53 is fixed to a driver 55, Fig. 7, which is slidably mounted on upper and lower guides 56 and 57 respectively as more clearly shown in Fig. 34. The driver 55 is driven by a link 58 which is operatively connected to a cam lever 59 in the form of a bell-crank including the arms 60 and 61, Fig. 2, the cam lever being driven by a cam 62 on the rotating shaft 63. The shaft 63 has a beveled gear 64 fixed thereto, Fig. 2, which meshes with a beveled gear 65 fixed to the power shaft 2, Fig. 2. The pusher 53 is driven from the main drive shaft 2 and intermittently reciprocates to push a package from the conveyor 51 onto the table 54 in a position directly opposite the wrapper in position 49 and properly centered with respect to the wrapper, there being a package stop 66, Fig. 7, to prevent unau-

thorized movement or shifting of the package on the table 54. A second pusher 67 is slidably mounted between guides 68 formed on the table 54 and moves the package in a predetermined position into a proper pocket 69 of an arm 70 in an intermittently rotating transfer wheel 71, Fig. 1.

Package transfer mechanism

The transfer wheel 71, Fig. 1, is fixed to a rotatably mounted shaft 72 and comprises a plurality of spaced arms 70. Each arm is provided with a cut-away portion or notch over which lies a plate 73 held in position by pins 74 and urged by springs 75. The position of the plate 73 with respect to the notched portion of the arm 70 forms the aforesaid pocket 69. The transfer wheel shaft 72 is given intermittent movement by a Geneva gear 76, Fig. 2, which is driven by means of an element 77 formed on an arm 78 fixed to a shaft 79. The shaft 79 has a gear 80 fixed thereto, which gear meshes with a gear 81 fixed to a shaft 82. The shaft 82 is driven by means of a chain 83 passing over a sprocket 84 on the shaft 82, Fig. 2, and a cooperating sprocket 85, Fig. 3, fixed to the shaft 2.

The pusher 67 has a lug 86, Fig. 12, fastened thereto, to which there is pivotally connected a link 87, Fig. 1, pivoted at 88 to one arm 89 of a drive lever 90. The driving lever 90 is pivotally mounted on a stud 91 and has its lower arm 92 pivoted to a link 93 as indicated at 94. This link 93 is pivotally connected to a crank 95 fixed to the shaft 82. Therefore, the pusher 67 is operated reciprocally from the shaft 82.

The feed rolls 46 and 47 move the severed wrapper with its attached tape to the position 49 as previously mentioned. The feed roll 47 carries a gear 96, Fig. 5, which meshes with a gear 97 on the shaft 98 upon which the feed roller 46 is mounted. Thus, the feed roll 47 is positively driven by the positively driven feed roller 46 through the gearing just described, Fig. 5. The shaft 98 has another gear 99 formed thereon, Fig. 6, which meshes with a gear 100 on the shaft 101. The shaft 101, Figs. 2, 6 and 7, has a sprocket 102 fixed thereto, Figs. 2 and 7, and is driven by a sprocket chain 103, Figs. 2 and 7, which is driven by a sprocket, not shown, mounted on the previously described driven shaft 79.

The conveyor 51 includes an endless belt which is driven by a pulley 104, Fig. 1, fixed to a shaft 105. The shaft 105, Fig. 6, has a gear 106 fixed thereto which gear meshes with an idler gear 107 mounted on an idler shaft 108. The idler gear 107 meshes with a gear 109 fixed to the previously described driven shaft 101. It may, therefore, be said that the belt of the conveyor 51 is driven from the shaft 101 through a train of gears.

The pusher 67, during its movement to the right, Figs. 7 and 12, will push the package 50, Fig. 12, to the right and engage the wrapper 10. The wrapper 10, Figs. 10 and 11, includes the cut portion 111 from the wrapper web 19 and the tape portion 112 from the tape web 34 which is secured to the portion 111 by the spot of adhesive as shown. The tape 112 extends a predetermined distance beyond the edge of the wrapper portion 111 to provide an easy opening tab 113, Fig. 10. The transfer wheel operates in proper timed relationship with the pusher 67 and, therefore, as the pusher 67 moves to the right, Fig. 12, and engages the package 50, the pocket 69 will be in alignment with the movement of the package. During the movement of the package into the pocket 69, the wrapper will pass between the angle 75

114 and the edge 116 of the plate 64, Fig. 12, thereby partially forming the wrapper about the package. Continued movement of the package into the pocket will position the package with 5 respect to the wrapper so that the wrapper will engage the top and bottom and one side of the package with the free edges of the wrapper extending a predetermined distance beyond the uncovered edge of the package. As soon as the 10 package with the wrapper partially formed thereabout is totally received in the pocket 68, the transfer wheel will rotate a partial revolution (in this case 90 degrees) to bring another pocket in position to receive the next package. Upon 15 movement of the transfer wheel, the package will be at the bottom of the wheel 71 in the position as clearly shown in Fig. 16 and in juxtaposition to the folder 116 and adhesive applicator 117, Figs. 15 and 16.

20 *Folder and adhesive applicator mechanism*

When the package is in the position shown in Fig. 16, the folder 116 will move upwardly in an arcuate direction to the right, Fig. 1, and fold the left flap, Fig. 16, from the dotted line position in that figure to the full line position as shown in Figs. 15 and 16 and against the side of the package. The folder 116 is fixed to the upper arm 118, Fig. 1, of a lever 119 which is pivoted 30 on a pivot shaft 120. The lower arm 121 of the driving lever 119 carries a cam follower 122 which is operated by a cam 123, Fig. 3. The cam 123 holds the free edge of the folder in position against the package as clearly shown in full lines 35 in Figs. 15 and 16. During this folding operation and after the free edge is folded against the package, the adhesive applicator will apply adhesive along the inner side of the sole remaining free edge. The applicator 117 is in the form of a 40 comb having teeth which have adhesive applied thereto from the adhesive in the container 124, Fig. 1. The applicator 117 is fixed to one arm of a U-shaped lever 125 which is pivoted at 126. The other arm of the U-shaped lever 125 is pivotally connected to a link 127 which is pivotally connected to a crank 128 on the shaft 79. As the applicator moves up to apply adhesive to the 45 inside free edge of the wrapper, the wrapper will be held by an abutment 129, Fig. 16. The abutment 129 is in the form of a shoe which forms a 50 guide 130 to cause the glued free flap to be pressed against the aforesaid folded flap and become fastened thereto during rotative movement of the transfer wheel another 90 degrees. When the transfer wheel has moved this last 55 90 degrees, making a total of 180 degrees from the time the package was first received by the transfer wheel, the package will be ejected from the wheel into a proper receiving channel or support 60 by suitable ejector mechanism.

Ejector mechanism

The ejector mechanism, Fig. 1, comprises a pair of spaced arms 131 which extend on opposite sides of the plate 73. These arms are fixed 65 to a slide block 132, Fig. 1, operating in upper and lower guides 133 and 134 respectively. The slide block is operated by a driven arm 135 and a connecting link 136. The arm 135 is fixed to a 70 rock shaft 137, Fig. 1. The shaft 137, Fig. 2, has a lever 138 fixed thereto which is pivotally connected at 139 to a link 140. The link 140 is pivotally connected at 141 to the gear 80 which is mounted on the aforesaid driven shaft 79. 75 Thus, during rotative movement of the shaft 79

and gear 80, the arms 131 will be given reciprocatory movement and, as the package is conveyed by the transfer wheel 71 to ejecting position, the arms 131, when they move to the right, Fig. 1, will engage the package near its ends 5 as shown in Fig. 18 and eject the package out of the pocket 68 and position the package in a guideway 142. The guideway 142 comprises spaced lower rails 143 and a central lower supporting rail 144 which support the package at 10 its ends and intermediate the ends as clearly shown in Fig. 22. The guide 142 also comprises an upper package engaging rail or bar 145 which is urged downwardly by the springs 146 arranged between the member 145 and the upper 15 member 147.

The arms 131 carry folding fingers 148 at their lower ends, Figs. 18 and 19. These fingers 148 are adjacent the ends of the package and are adapted to fold the wrapper inwardly along one 20 side of the package at the ends thereof as clearly shown in Figs. 18 and 19. These fingers 148 are provided with slots or recesses 149 which are adapted to receive the stationary tucking folders or fingers 150 against which the wrapper on 25 the other side of the package is being pushed during the ejecting movement of the package from the transfer wheel 71. Thus, as the package is moved from the transfer wheel 71 and onto the guide 142, the wrapper overhanging the ends 30 of the package on both sides thereof will be tucked or folded inwardly as clearly shown in Figs. 18, 19 and 20, particularly Fig. 20. When the arms 131 reach the extreme end of their 35 ejecting movement, the edge folded by the fingers 148 will be positioned so that those folds will lie inwardly of the stationary folders 150. Thus, the folds on both sides of the package and at each end will be folded snugly against the package and maintained in that position by the 40 stationary folders 150. At the end of the ejecting movement of the package and after the package has been moved a predetermined distance in 45 the guideway 142 by the arms 131, transport or conveying mechanism 151 engage the package 45 which is then positioned between the stationary rigid folders or fingers 150 and continues the movement of the package along the guideway 142 where other tucking and folding mechanism operates.

Transport mechanism

The transport mechanism comprises a pair of arms 151 carrying spaced fingers 152, Figs. 1 and 22, which intermittently engage successive packages and move them forwardly along the guideway 142. This transport mechanism may be of any conventional type or design just so it performs the function intended. In the present instance this transport mechanism is moved to the right, Fig. 1, to engage and move the packages and then recedes with a backward, downward movement, being operated in the present case through a system of cams 153 mounted on the shaft 2. Therefore, the transport mechanism will operate synchronously and in timed relationship with the other operating elements and mechanism. As the package 50 is being moved along the guideway 142 by the transport mechanism 151, the free edges of the package at the bottom thereof will become engaged with inclined 60 rigid stationary folders 154.

Folding mechanism

The folders 154 incline upwardly and become thicker as the package progresses along its path, 75

while the fingers 150 decrease in size. Therefore, this progressive movement of the package along the guideway will fold the flaps along the bottom of the package at the ends thereof upwardly to the positions first shown in Fig. 22 and finally to the position shown in Fig. 25. The folders 154 hold the folded flap tightly against the ends of the carton or package as clearly shown in Fig. 25 throughout the movement of the package along the guideway and until the upper flap is to be folded. While the package is still on the guideway and held by the folders 154, the free top flaps at the ends of the package are given an application of suitable adhesive by an adhesive applicator.

Adhesive applicator

This adhesive applicator, Figs. 23 and 24, comprises a bracket 155 which is fastened to a part 20 of the frame 1 and includes a base 156 which is located a predetermined distance below the bottom of the guideway 142. A shaft 157 journaled in suitable bearings in the bracket and frame is driven by a gear 158, Fig. 23, which meshes with an idler gear 159, Fig. 2, the idler gear being driven by gear 81 on shaft 82, Fig. 2. The shaft 157 carries gears 160 which mesh with gears 161 on shafts 162 supported by the reservoirs 163. Applicators 164 in the form of disks are fixed to the ends of the shafts 162 and extend down a predetermined distance into the reservoirs 163 so as to obtain adhesive in these reservoirs and apply it to the projecting end flaps on the top of the package at the ends thereof. These disks 164 are positioned so as to apply adhesive to the inside of the remaining flaps, the said disks being positioned outwardly of the rigid folders 154 as clearly shown in Fig. 24. The disk is so constructed and arranged that its periphery will be substantially coincident with the inside of the flap to be glued so that the inside edges of the end flaps will come in contact with and be engaged by the periphery of the rotating disk which has the adhesive applied thereto. Flap guides 165 may be fastened to a part of the guideway 40 and extend downwardly as clearly shown in Fig. 24 so as to positively insure the flap coming into contacting engagement with the adhesive carrying disk to insure adhesive being applied thereto. The members 166 may be provided with inclined tail-pieces 166 so as to insure the positioning of the flaps with respect to the disks. After the gluing operation, the transport mechanism moves the package still further along the guideway to the extreme outer right-hand end thereof, the package being constantly held by the fingers 154. At the end of the guideway the package with the extending glued tabs is ejected or moved to position to be acted upon and to be engaged by the delivery mechanism which folds the remaining flaps against the ends of the package where they become glued.

Delivery mechanism

Delivery mechanism is located at the extreme right-hand end of the guideway 142, and comprises two spaced disks 167, Figs. 28, 29 and 30, fixed to a rotary shaft 168, there being a spacer 169 arranged between the disks and fixed thereto. The shaft 168 is supported in suitable bearings in 70 an attaching bracket 170, which is fixed to a part of the frame 1. A gear 171 is fixed to the shaft 168 and drives the same, obtaining its driving power from an idler gear 172, which meshes with 75 a gear 173 fixed to the aforesaid driven shaft 168.

The distance between the spaced disks 167 is considerably less than the length of the package. The package, therefore, extends a predetermined distance beyond the outer faces of the disk. A stationary cam 174 is arranged at one side of a disk 167, and operates a plurality of carrying arms or fingers 175, which are pivotally connected to the disks by means of transverse rods 176. These fingers carry lugs 177 preferably formed integrally therewith, and are held against the cam by springs 178, Fig. 28. The springs 178 hold the lugs 177 against the periphery of the cam 174. Thus, during rotative movement of the disks, the arms are moved throughout a plurality of angular positions. In delivery position the arm will be in the position shown in Fig. 28, whereby a package 80 will rest upon the arms 175 with the right-hand side of the package engaging the peripheral surface of the disks. During rotative movement of the disks the lugs 177 will be engaged with 20 the smooth circular surface of the cam until their associated arms 175, upon which the packages rest, attain the upright position shown in Fig. 28, in which position the packages will be arranged in adjacent relationship on a receiving guide or 25 platform 179. During continued rotation of the disks, the lug or shoe 177 will follow the cam surface of the cam 174 causing the fingers 175 to be moved to the various positions shown in Fig. 28. These positions are attained because the 30 springs 178 hold the lugs or shoes 177 in constant engagement with the periphery of the disk. Therefore their angular position is adapted to be changed as set forth. An arcuate spaced plate 180 extends a predetermined distance on each 35 side of the pair of disks 167, the space between said plates being substantially equal to the length of the package. Therefore, when the package is moved from the position designated by the letter A in Fig. 28 to the position B with the disks rotating in the direction of the arrow in Fig. 28, the 40 extending flap on the upper side of the package at each end thereof will be pressed down against the ends of the package. In other words, the 45 extending flaps on the package are pressed between surfaces spaced a distance apart substantially equal to the length of the package. Therefore, when the package is pushed within this space, the flaps are caused to fold downwardly against the ends of the package, and as the 50 insides of these flaps have an adhesive applied thereto, the flaps will be permanently stuck to the bottom and side flaps causing the package to be completely wrapped and sealed. The spaced plates 180 extend substantially one quarter of the 55 way around the disk, from receiving position to discharging position. Therefore, the ends of the flaps are caused to hug the side walls and become pressed tightly against the ends of the package. A spring-pressed top plate 181 may be arranged 60 above the receiving table 179, as shown in Fig. 28, to maintain the packages in proper position.

Tape guide

In view of the fact that the tape 34 is fed 65 faster than the wrapper 19, means are provided to guide, support and position the tape to maintain it in a certain position with respect to the wrapper. Due to the fact that the tape which is secured to the wrapper at only one point is relatively narrow and has a tendency to shift and curl, the present tape guide mechanism is provided. This guide mechanism comprises a guide shoe 182, Figs. 1 and 5, which is relatively long 70 vertically and adapted to reciprocate vertically 75.

and engage the tape. When the tape 34 is fed, the shoe moves with the tape in the same direction in which the tape is fed and maintains the tape in a proper position with respect to the 5 wrapper 19. This tape guide is timed so as to follow the timed movement of the knives so that when the leading or lower edge of the tape is in a position to enter the guides 44 and 45, this 10 tape guide will hold the tape adjacent to the wrapper and prevent it from curling or shifting its position. When the cutters tend to approach each other, the shoe 182 is moving away and upwardly so as to not foul the knives. The parts are so timed and constructed that the shoe 182 15 will be at the extreme upward position of its travel during the actual cutting operation and immediately after the cutting operation will drop down and guide the tape as previously mentioned. Therefore the shoe moves upwardly and 20 downwardly to guide the tape in proper timed relationship with respect to the actual cutting of the knives 29 and 30. Also, this guide serves to stick the tape to the wrapper because, as previously described, the wrapper, prior to being cut, 25 is provided with a smooth dab of glue in a position so as to be in alignment with the tape. Therefore, this shoe pushes the tape against the wrapper and assists in maintaining the stuck connection. The upper edge of the shoe 182 extends 30 between the feed rollers 15 and 37, Fig. 5, said rollers being grooved or relieved to receive the upper end of the shoe. The shoe is provided with a tail-piece 183 fastened to a guide block 184. The guide block 184 carries pins 185 which extend 35 through suitable apertures provided in a guide yoke 186 which is rigidly fastened to a block 187 connected to the bracket 22. A bell-crank 188 has one arm thereof 189 connected to the slide block 184 by a pin and slot connection 40 designated generally by the numeral 190, Fig. 4, and its other arm 191 pivotally connected to a link 192, Fig. 1. The bell-crank is pivotally mounted on a stud or shaft 193, Fig. 1. The link 192 is also connected to a bell-crank 194 which bell-crank 194 is pivoted at 195, Fig. 1, and has 45 a cam follower 196 which engages a cam 197 mounted on the previously mentioned shaft 23. This cam follower 196 is maintained in constant engagement with the cam 197 in any well known manner, such as by a spring (not shown).

Another mechanism for assisting in maintaining the tape in proper position with respect to the wrapper comprises a tape locator or positioner 198 as shown in Figs. 8 and 9. This tape positioner 198 is located immediately below the table 50 and has its tape locating ends arranged in proper position with respect to the guide 43 to maintain the tape in a predetermined position with respect to the wrapper when the wrapper is 55 arranged in the position designated formerly by the numeral 49. The positioner 198 comprises a pair of cross levers 199, Figs. 8 and 9, pivoted at 200, and includes pusher arms 201. The pusher arms are maintained in open position as shown 60 in Fig. 9 until the tape is arranged therebetween at which time the jaws will close as shown in Fig. 8 to properly position the tape. The ends 201 of the positioner 198 are normally urged in closed position by means of a pin and spring 202 and 65 203 respectively and are forced open by means of a cam 204, the cam surface 205 of which is adapted to cooperate with pins 206. Therefore, when the cam is in the position shown in Fig. 8, the cam surface 205 will have no effect on the 70 pins and the spring 203 will close the ends 201

to the position shown in that figure. However, upon reverse movement, the cam surface 205 will be engaged by the pins 206 spreading the levers 199 and opening the arms or jaws 201 as shown in Fig. 9. A pin 207 carried by the plate 54 is arranged centrally between the arms 201 and prevents the spring 203 from completely closing the arms. The cam 204 is rigidly fastened to the reciprocating pusher 67 and, therefore, operates during the operation of the 10 pusher 67.

To assist in maintaining the wrapper in proper position with respect to the package, a tucker or kinking finger 208, Figs. 13 and 14, is arranged at each end of the package so that when the package strikes the wrapper as the package is being moved into the pocket 69 of the transfer wheel 71, the ends of the wrapper will receive a pre-kink or fold, thereby assisting in maintaining the wrapper in proper position with respect 15 to the package and preventing the wrapper from shifting with respect to the package during movement of the package into the pocket 69.

Detector mechanism

It is desirable that the webs 19 and 34 be not fed when a package to be subsequently wrapped at a predetermined time is not present in order that no wrapper or tape may be cut when no package to be wrapped is at a predetermined 20 position on the feed conveyor. Detector mechanism is, therefore, provided to prevent the cutting of a wrapper if no package is fed. In other words, if no package is present at a predetermined point on the conveyor, the mechanism for feeding the wrapper web and the tape web and the mechanism for the cutters will be maintained inactive until such time as a package is present at the said predetermined position. However, this detector mechanism in no way affects the operation of the machine as regards the already cut wrappers and the packages which have already passed beyond the detector mechanism. In this respect only the web feed mechanism and the cutters are prevented from operating while the rest of the machine continues to perform its normal cycle of operation. This detector mechanism comprises a detector element 209, Figs. 7 and 32 to 36, which is rigidly attached to an arm or lever 210 pivoted at 211 and having a rigid offset rear portion 212 (Figs. 7 and 32 to 38). A cam 213 is formed on the upper edge of the member 210 on the arm 212 thereof rearwardly of the pivot 211 and is adapted to be engaged by a pawl or cam operator 214 carried by the first mentioned pusher 53. Therefore, when the pusher 53 moves forwardly to displace a package from the belt of the conveyor mechanism 51, the pawl or cam operating mechanism 214 will operate on the cam 213 and depress the arm 212, causing the forward end 209 to raise. However, continued forward movement of the pusher 53 will move the pawl 214 off of the cam surface 213 and allow the lever 212 to move upwardly causing the member 209 to move downwardly, there being a spring 215 fastened to the end of the lever 212 to pull this end in an upward direction. In other words, there is always a tendency of the detector element 209 to be urged downwardly and maintained in that position except when the pawl 214 is in engagement with the cam 213. Therefore, if there is a package on the belt beneath the detector element 209, the packages are free to slide thereunder, but if there is no package in the proper predetermined position, the detector element 209 70 75

will move downwardly and prevent improper feeding of packages into the machine. Therefore, the packages are fed in proper timed relationship with the operation of the detector element 209. In order to prevent the detector element 209 from raising on the return movement of the pusher 53, the pawl 214, which is pivoted to the pusher 53 at 215, will engage a finger 216 (Figs. 7 and 37) and be rotated thereby so that it will 5 not engage the cam 213 upon the rearward or return stroke of the pusher 53. Therefore, upon forward movement of the pusher 53, the cam will be depressed, causing the detector end 209 to be raised a short period of time until the member 10 214 slides off the cam 213 at which time the detector 209 will be in its down position. Upon return movement of the pusher 53, the pawl will be prevented from coming in contact with the cam 213. In other words, the cam 213 is only engaged 15 once and that is on the forward movement of the pusher. The detector element 209 is normally urged downward by means of the spring 215. At the end of the return movement of the pusher 53, the element 214 will strike a stationary member or finger 217 (Figs. 7 and 37) and be rotated thereby to its original position as clearly shown in Fig. 7. When the detector 209 is held in its intermediate position, by its engagement with the top of a package, the package is free 20 to continue movement along the conveyor and into the machine and the webs will continue to be fed and cut. If, however, there is no package under the detector element 209, the detector element 209 will drop until it engages the belt of the conveyor means 51 and will remain in that position and prevent on-coming packages from passing through the machine and becoming improperly positioned until the next forward movement of the pusher 53 causes the 25 cam to become engaged by the pawl 214, thus raising the detector. If there are other packages on the machine, they will engage the detector element 209 and be temporarily held from being fed. Thus, during the next cycle of operation, 30 when the detector element is again raised by means of the pawl 214 engaging the cam 213, these packages will be permitted to feed through the machine in regular proper order and in timed relation with the pusher 53.

50 When there is a package on the belt under the detector, the feeding and cutting means will operate so as to provide a wrapper for that package, but if no package is under the detector when it descends, it will operate mechanism to prevent feeding of the wrapper and also to prevent the cutting knives from operating. The end of the lever 212 carries a rod 218, Fig. 32, having a lug 219 formed on its lower end. The position of this lug determines whether or not the wrapper feed mechanism and cutters are to operate.

60 The arm 220 of a bell-crank 221, pivoted at 222, Fig. 35, is operated by the arm 223, Figs. 2 and 3, of the said bell-crank engaging a cam 224 fixed to the driven shaft 63. During rocking 65 movement of the arm 220 of the bell-crank 221, the arm 220 will engage the lug 219 and force it against a lug 225 which is rigidly fixed on an arm 226 also pivoted on the shaft 222. A spring 220', Fig. 36, is connected to the arm 221 and the lug 70 219 and holds these two members in contact. This spring prevents the members from swinging idly, but at the same time permits vertical movement of one member relative to the other. Movement of the arm 226 caused by the arm 223 engaging 75 the lug 219 and forcing it to engage the lug 225

and move the lever 226 will shift the arm 226 about its axis 222 and move the clutch operating arm 227 to the left, Fig. 35, there being a link 228 operatively connecting the clutch arm 227 to the lever 226.

Clutch mechanism

Movement of the clutch arm 227 to the left, Fig. 3, causes disengagement of the clutch 229 from operating the part 10 of the shaft 8 which controls the operation of the feeding and cutting mechanism. The clutch 229 comprises a clutch collar 230, Fig. 42, which is fixed to the part 9 of the shaft 8, and a second clutch collar 231 which is slidably mounted on the part 10 of the shaft 8. This clutch mechanism 229, therefore, causes the connecting and disconnecting of the parts 9 and 10 of the shaft 8, and therefore controls the operation of the feed and cutter rolls. Inasmuch as the cam which controls the adhesive applicator arm 41 is operated by the same mechanism which operates the cutter rolls, this arm will not operate when the feed and cutter rolls do not operate. The cam is operated directly from the cutter roll shafts and naturally when the cutter rolls do not operate, the cam shafts and cam will not operate. Therefore, the sticker arm 41 will not operate. When the clutch operating arm 227 is shifted by the movement of the lever 226 to the left in Fig. 3, a collar 232 will first disengage the clutch pawl 233 from the pawl receiving notch 234, Fig. 42, in the collar 230 and then shift the clutch portion 231 out of engagement with the clutch collar 230. The clutch 35 pawl or pin 233 is spring-pressed into its receiving notch 234 by a spring 235 (Fig. 40). This pawl is disengaged from its notch or keeper 239. Therefore, when the lever 227 is shifted to the left, the clutch collars 230 and 231 are disengaged 40 and the pawl or pin 233 is also disengaged. The part 9 of the shaft 8 will, therefore, become disengaged from part 10 of the shaft 8. Therefore, upon disengagement, the continuously operating part 9 of the shaft 8 can no longer rotate the part 10 of the shaft 8 and inasmuch as the feeding and cutting mechanism is driven from the part 10 of the shaft 8, the feeding and cutting mechanism will become inactive when the clutch is 45 disengaged. The clutch will be maintained in its out-of-engagement position until it is again positively connected which connection will not occur until a package is in proper position under the detector element 209. To maintain the clutch out of engagement and in operative position, there is provided an arm 236 pivotally connected to the clutch operating arm 227 at 237, Fig. 3. This arm 236 has a rigid extension 238 having a receiving recess 239 which is adapted to receive a pin 240. When the movement of the clutch 50 operating arm 227 is all the way to the left to cause disengagement of the clutch, the pin 240 is engaged by the locking end 239 as shown in Fig. 33. The locking engagement of the pin 240 with the extension 238 occurs due to the fact that the arm 236 is freely pivoted at 237 and therefore when the clutch operating lever 227 swings to the left, the lower arm 236 will swing to the right causing the part 238 to move to the left and upwardly until the locking end 239 is 55 engaged by the pin 240 as clearly shown in Fig. 33. During the next cycle of operation, should there still be no package under the detector element 209, the parts will remain in said locked position with the clutch out of engagement. However, 60

should there be a package under the detector arm 209 during the next cycle of operation, lug 219, Fig. 33, will be in its lowermost position and engage the end 241 of the arm 236. When the arm 221 moves toward the left, the movement of the lever 236 to the left will then free the locking end 239 from the pin 260 and cause disengagement of these parts and permit the clutch arm 227 to be moved to the right, disengaging the clutch collar 232 from the part 231 and again permitting the clutch to become engaged at which time the parts 9 and 10 of the shaft 8 will again become united to again operate the feeding and cutting mechanism. In cases where the detector arm comes into contact with a package during each cycle of operation, the lug 219 will be in its lowermost position and not in engagement with the lug 225 and away from the lever 236 so that the clutch operating lever 227 will not be moved by the movement of the rock arm 221. The clutch will therefore remain in engagement, the parts 9 and 10 of the shaft 8 will be connected and the feeding and cutting mechanism will operate in its regular normal operative manner. The clutch 229 is normally urged a predetermined distance toward the right, Fig. 39, by the springs 242 surrounding the pins 243, the clutch operating collar 232 moving the collar 231 away from the companion collar 230 against the tension of the springs 242. The clutch operating arm 227 is normally urged in a predetermined position by a spring 227', Figs. 3 and 35, there being a stop plate 227" to limit the movement of the arm by the spring. An end ball-bearing thrust bearing 244, Fig. 39, is provided to insure free and easy rotative movement of the parts during engagement of the clutch. When the clutch first becomes disengaged, there is a tendency of the clutch collar 231 over-riding, that is, continuing to rotate and consequently this tendency is transmitted to the feeding and cutting mechanism. Therefore, to prevent this over-riding action of the clutch due to kinetic energy, a piece of friction material 245 is fastened to the clutch collar 231 and engages the collar 232. Therefore, when the clutch is thrown out of engagement and the collar 231 is moved away from the collar 232, the friction material on the collar 232 will stop the rotation of the part 10 of the shaft 8 immediately.

50 Preferred detector mechanism

A more simple detector mechanism, and the one which is preferably used, is shown in Figs. 47 to 49 inclusive. In this latter embodiment the belt of the conveyor mechanism 51 is widened as indicated at 300, Fig. 48 and the detector element 209 acts only as a package detector and not as a timer. In this latter embodiment the detector 209 is not controlled by the operation of the pusher 53 and no cam element 213 or pawl 214 is required. The detector element 209 is always in its lowermost position and an auxiliary plunger 301 is provided to push a package 50 under the detector in the manner shown in Fig. 48. Thus, when there is no package in position against the stop 302, the detector element 209 will be in its lowermost position as shown in Fig. 49 and cause operation of the clutch 229. If, however, there is a package under the detector, the mechanism will function continuously, as required. The auxiliary plunger 301 pushes the package from the end of its travel against the stop 302 in a forward direction, against the stop 303 where it will clear the stop 302 and then be

carried further against the stop 52 where it is in proper position to be engaged by the pusher 53 upon its next forward movement as shown in Fig. 47. The pusher 53 pushes the package 50 in proper position relative to the second pusher 67 where the subsequent cycle of operations is completed as previously described.

Rotary folders

Instead of employing the tuckers and folders 148 and 150, as previously described, it may be advantageous to use rotary tuckers and folders as shown in Figs. 43 to 46 inclusive wherein continuously rotating fingers 400 are provided on each side of the package. Thus, when the package is moved from the transfer wheel 71 by the arms 131, the rotary fingers 400 will rotate in the direction shown by the directional arrow in Fig. 43 and tuck or fold the wrapper along one side of the package at the ends. This tucking or folding operation occurs because the fingers 400 are operating at a speed greater than the movement of the package 50. These fingers are in timed relationship with respect to the progressive movement of the packages so that a package will be engaged during each complete revolution of a finger. The finger 400 has a blunt rounded end 401 which engages the overhanging wrapper at one side of the package and pushes it inwardly against the ends of the package. The rotary folder moves with and faster than the package, but has a relatively long engaging surface 402. These fingers are recessed at 403, Fig. 45, so as to receive the ends of the stationary folders 404. Thus, as the package is being advanced in the direction shown by the arrow in Fig. 44, the right-hand side of the wrapper extending from the end of the package will be engaged by the stationary folder 404 and cause the wrapper along that side to be folded inwardly. The rotary folder, however, remains in contact with the fold made by it until that fold is received behind the stationary folder 404. The rotatably mounted tuckers or folders 400 are mounted on shafts 405 which are rotated synchronously and in timed relationship with other operating parts of the machine.

The invention provides a packaging machine which feeds packages to be wrapped along a predetermined path, feeds wrapping web and tape web from individual rolls and in proper timed relationship and in proper position relative to each other and then simultaneously cuts the two webs positioning them in proper position relative to each other and to the package, seals and wraps the wrapper and its cooperating tape about the package leaving a tab to permit the package to be easily opened. Also, the invention contemplates the use of selector mechanism which prevents operation of the feeding and cutting device if a package does not assume a predetermined position on the machine. Furthermore, the machine permits such packages as are already fed into the machine to be wrapped by wrappers already cut even though the web feeding and cutting mechanism has been stopped. The novel folders or tuckers of the various types shown and described cause the wrapper to be positively and neatly folded about the package and properly sealed.

The operation of the complete machine has been described throughout the progress of the specification and during the description of the parts and, therefore, further remarks covering the operation are not made.

Changes may be made in the form, construction and arrangement of the parts without departing from the spirit of the invention or sacrificing any of the advantages thereof, and the right is hereby reserved to make all such changes as fairly fall within the scope of the following claims.

The invention is hereby claimed as follows:

1. A wrapping machine comprising means for feeding a web to a predetermined position, means for cutting a wrapper of a predetermined length from said web, means for positioning a tape upon the wrapper, means for moving packages to a position to be engaged by said wrapper, means for supporting the wrapper, means for holding the tape against lateral movement with respect to the wrapper, means for pushing the package against the wrapper while the tape is held thereon to fold the wrapper about three sides of the package, means for folding the free edges of the wrapper about the other side of the package, and means for folding the wrapper about the ends of the package. 10
2. A wrapping machine comprising means for feeding a web to a predetermined position, means for cutting a wrapper of a predetermined length from said web, means for positioning a tape upon the wrapper, means for moving packages to a position to be engaged by said wrapper, means for supporting the wrapper, means for holding the tape against lateral movement with respect to the wrapper, means for pushing the package against the wrapper while the tape is held thereon to fold the wrapper about three sides of the package, means for folding one free edge of the wrapper about the remaining side of the package, means for applying an adhesive to the other free edge of the wrapper, means for folding said last named free edge about said remaining side of the package and overlapping the first named free edge, and means for folding and fastening the wrapper about the ends of the package. 20
3. Feeding mechanism for wrapping machines comprising feed rolls, means for feeding a wrapper to the feed rolls, a driven shaft for operating the feed rolls, a drive shaft for operating the driven shaft, clutch mechanism for connecting or disconnecting said two shafts, detector mechanism for controlling the operation of the clutch to move the clutch to engaged or non-engaged positions, latch means for maintaining the clutch in non-engaged position, and means for disabling said latch means. 30
4. Feeding mechanism for wrapping machines comprising cutter rolls, means for feeding a web of wrapping material to said cutter rolls at a predetermined rate of speed, means for feeding a web of tape to said cutter rolls at a rate of speed different from the feeding rate of the wrapping web, and means for fastening the tape to the wrapper prior to the cutting operation. 40
5. Feeding mechanism for wrapping machines comprising cutter rolls, means for feeding a web of wrapping material to said cutter rolls at a predetermined rate of speed, means for feeding a web of tape to said cutter rolls at a rate of speed different from the feeding rate of the wrapping web, means for fastening the tape to the wrapper prior to the cutting operation, means for moving the wrapper and attached tape to a predetermined wrapping position, and means for preventing shifting or curling of the tape during such movement. 50
6. A wrapping machine comprising cutters, means for feeding a wrapper web and a tape web at different speeds to the cutters, means for cutting both of said webs simultaneously, means for fastening the tape to the wrapper prior to the cutting operation, means for feeding the tape and wrapper to a predetermined position relative to a package to be wrapped, tape positioning means for positioning said tape relative to the wrapper, means for pushing a package through the wrapper to partially fold the wrapper about the package, folding and fastening means for folding the free ends of the wrapper about a side edge of the package, and sticking said free edges together, end folding means comprising movable fingers for folding the wrapper at the ends of the package on one side thereof, stationary fingers against which the opposite side of the wrapper at the ends is folded, said movable fingers having an opening therein to receive the stationary folder. 60
7. A wrapping machine comprising cutters, means for feeding a wrapper web and a tape web at different speeds to the cutters, means for cutting both of said webs simultaneously, means for fastening the tape to the wrapper prior to the cutting operation, means for feeding the tape and wrapper to a predetermined position relative to the wrapper, means for pushing a package through the wrapper to partially fold the wrapper about the package, folding and fastening means for folding the free ends of the wrapper about a side edge of the package and sticking said free edges together, end folding means comprising movable fingers for folding the wrapper at the ends of the package on one side thereof, rotary folders engaging the end of the wrapper to fold the wrapper on the ends of the package on the opposite side thereof, said movable fingers having slots provided therein to receive the rotary folders during the folding operation of the rotary folders. 70
8. Method of wrapping a wrapper and an opening tab about a package, which consists in feeding a wrapping web and a tape web at different rates of speed so that a part of the tape material will extend beyond the edge of the wrapping material, fastening the tape to the wrapper, cutting the webs simultaneously to form wrappers, moving a package through the wrapper and tape, folding and fastening the free edges of the wrapping material about a side of the package with the tape extending therebeyond, and finally folding the wrapper about the ends of the package. 80
9. In a wrapping machine, a cutter, means for feeding a web of wrapping material to said cutter, means for feeding a web of tape to said cutter, means for applying adhesive to the web of wrapping material prior to its severance by said cutter, and guide means movable from a position in advance of said cutter to force said web of tape in contact with said web of wrapping material to a position beyond said cutter to prevent shifting of the tape relative to the wrapper during the cutting operation. 90
10. Feeding mechanism for wrapping machines comprising a cutter, means for feeding a web of wrapping material to said cutter, means for feeding a web of tape to said cutter, and means comprising an intermittently operable spot gluing mechanism for fastening the tape to the wrapper prior to the cutting operation. 100
11. Feeding mechanism for wrapping machines comprising a cutter, means for feeding a web of wrapping material to said cutter, means for feeding a web of tape to said cutter, means comprising an intermittently operable spot gluing mecha- 110

nism for fastening the tape to the wrapper prior to the cutting operation, means for moving the wrapper and attached tape to a predetermined wrapping position, and means for maintaining the tape in a predetermined position relative to the wrapper during such movement to prevent shifting or curling of the tape.

12. In a wrapping machine, means for feeding a sheet of wrapping material, means for conveying an article to be wrapped to a predetermined position in alignment centrally of said sheet of wrapping material, a rotary wrapping member having a receiving arm for folding said sheet about three sides of said article and means for pushing the article against the sheet of wrapping material and into said receiving arm, causing said sheet to be folded about said article, an adhesive applicator and a folding means operable during the rotation of said wrapping member to apply adhesive to one of the free edges of said sheet and to fold the other of said free edges about the remaining sides of said article, means operable during the further rotation of said rotary member to fold the adhesive containing free edge into contact with the other of said free edges, means for ejecting the partially wrapped article from said rotary member, means thereafter operable to apply adhesive to the ends of the wrapper, and means to fold said ends about the article.

13. In a wrapping machine, means for successively feeding a plurality of wrappers, means for successively conveying articles to be wrapped to a predetermined position in juxtaposition to said wrappers, a rotary wrapping member having a plurality of receiving arms, means for intermittently rotating said member successively to align said arms with the aligned article and wrapper, means for pushing the leading article against the leading wrapper and into the aligned receiving arms to cause said arms to fold the wrapper about three sides of said article, an adhesive applicator and a folding means operable during the rotation of said wrapping member to apply adhesive to one of the free edges of said sheet and to fold the other of said free edges about the remaining sides of said article, means operable during the further rotation of said rotary member to fold the adhesive containing free edge into contact with the other of said free edges, means for ejecting the partially wrapped article from said rotary member, means thereafter operable to apply adhesive to the ends of the wrapper, and means to fold said ends about the article.

14. In a wrapping machine, means for feeding a wrapper and a package, means for folding the wrapper about the sides of said package, a pair of movable transfer fingers engaging the opposite end portions of one side of said wrapper to form a tuck about the end of the package, a pair of stationary fingers engaging with the opposite end portions of the other side of said wrapper, said stationary fingers cooperating with said transfer fingers to form a tuck about the opposite end of said package, and means thereafter operable to fold and fasten the remaining end portion of the wrapper about the ends of the package.

15. In a wrapping machine, means for feeding a wrapper and a package, means for folding the wrapper about the sides of said package, a pair of movable transfer fingers engaging the opposite end portions of one side of said wrapper to form a tuck about the end of the package, a pair of stationary fingers engaging with the opposite end portions of the other side of said wrapper, said stationary fingers cooperating with said transfer

fingers to form a tuck about the opposite end of said package, a pair of spaced stationary members engaging with one portion of each end of said wrapper, transfer means for moving said package from the stationary tucking fingers to said last mentioned stationary members for causing said end portions to be folded thereby about the ends of said package, means for applying adhesive to the remaining portion of each end of the wrapper, a rotary transfer member receiving the package from said transfer means, and stationary members engaging said remaining portions and cooperating with said rotary transfer member to force said end portions into contact with the adhesive-containing end portions.

16. In a wrapping machine, means for folding a wrapper about three sides of a package and end folding means comprising movable fingers for folding a wrapper at the ends of the package on one side thereof, rotary folders engaging the end of the wrapper to fold the wrapper on the ends of the package on the opposite side thereof, said movable fingers having slots provided therein to receive the rotary folders during the folding operation of said last mentioned folders.

17. A machine for wrapping a wrapper about a package, comprising a driven shaft, feeding and cutting mechanism driven from said shaft, means normally connecting said driven shaft to said feeding and cutting mechanism, a continuously operable member, a normally inactive member operable to release said connecting means, a package engaging detector operable in the absence of a package to be wrapped to connect said continuously operable member to said normally inactive member to operate the latter and release said connecting means, means for latching said normally engageable member in operated position, and means controlled by the detector for disabling said latching means.

18. A machine for wrapping a wrapper about a package, comprising a driven shaft, feeding and cutting mechanism driven from said shaft, means normally connecting said driven shaft to said feeding and cutting mechanism, a continuously operable member, a normally inactive member operable to release said connecting means, a package engaging detector operable in the absence of a package to be wrapped to connect said continuously operable member to said normally inactive member to operate the latter and release said connecting means, means for maintaining said connecting means in released condition, and means operable by said detector for connecting the continuously operable member to said maintaining means whereby to restore said connecting means to normal condition when a package to be wrapped engages said detector.

19. A wrapping machine comprising means for feeding a plurality of wrappers, means for feeding a plurality of packages to wrapping position with respect to said wrappers, means for wrapping the wrappers about the packages, a continuously operable member, a normally inactive member operable to render both said feeding means inoperative, a package-engaging detector operable in the absence of a package to be wrapped to connect said continuously operable member to said normally inactive member to operate the latter and render said feeding means inoperative.

20. A wrapping machine comprising means for feeding a plurality of wrappers, means for feeding a plurality of packages to wrapping position with respect to said wrappers, means for wrap-

- ping the wrappers about the packages, a continuously operable member, a normally inactive member operable to render both said feeding means inoperative, a package-engaging detector operable in the absence of a package to be wrapped to connect said continuously operable member to said normally inactive member to operate the latter and render said feeding means inoperative, means for maintaining said feeding means inoperative, and means operable by said detector for restoring said feeding means to operative condition when the package to be wrapped engages said detector.
21. In a wrapping machine, a cutter, means for feeding a web of wrapping material to said cutter, means for feeding a web of tape to said cutter, means in advance of said cutter for applying adhesive to the web of wrapping material, and means shiftable bodily with said web of tape to force the same into contact with said web of wrapping material and to prevent shifting or curling of the tape relative to the wrapper during feeding movement of the webs in the cutting operation.
22. In a wrapping machine, means for feeding a wrapper web, means for feeding a tape web, means for superimposing the tape web upon the wrapper web, said tape web feeding means being operable at a faster rate than the wrapper web feeding means whereby the end of the tape will project beyond the end of the wrapper as the tape is superimposed with respect to the wrapper, cutter means for cutting lengths from the superimposed wrapper and tape webs, and means for wrapping articles in said lengths.
23. In a wrapping machine, means for feeding a wrapper web, means for feeding a tape web, means for superimposing the tape web upon the wrapper web, means for cutting lengths from said combined webs, means for wrapping articles in said lengths, and guiding means associated with said cutting means engageable with the tape and movable bodily therewith as the tape moves from the cutting means to the wrapping means to hold the tape against inadvertent displacement with respect to the wrapper.
24. In a wrapping machine, means for feeding a wrapper web, means for feeding a tape web, means for superimposing the tape web upon the wrapper web, said tape web feeding means being operable at a faster rate than the wrapper web feeding means whereby the end of the tape will project beyond the end of the wrapper as the tape is superimposed with respect to the wrapper, cutter means for cutting lengths from the superimposed wrapper and tape webs, means for wrapping articles in said lengths, and guide means engageable with the tape and shiftable bodily therewith during movement of the tape from the cutter means to the wrapping means whereby to preclude inadvertent movement of the tape with respect to the wrapper.
25. In a wrapping machine, means for feeding a wrapper web, means for feeding a tape web, means for superimposing the tape web upon the wrapper web, said tape web feeding means being operable at a faster rate than the wrapper web feeding means whereby the end of the tape will project beyond the end of the wrapper as the tape is superimposed with respect to the wrapper, cutter means for cutting lengths from the superimposed wrapper and tape webs, means for wrapping articles in said lengths, and holding means associated with the wrapping means engageable with the projecting end of the tape for holding the tape against inadvertent lateral movement with respect to the wrapper during the initial operations of the wrapping means.
26. In a wrapping machine, means for feeding a wrapper web, means for feeding a tape web, means for superimposing the tape web upon the wrapper web, said tape web feeding means being operable at a faster rate than the wrapper web feeding means whereby the end of the tape will project beyond the end of the wrapper as the tape is superimposed with respect to the wrapper, cutter means for cutting lengths from the superimposed wrapper and tape webs, means for wrapping articles in said lengths, and holding means associated with the wrapping means engageable with the projecting end of the tape for holding the tape against inadvertent lateral movement with respect to the wrapper during the initial operations of the wrapping means, said holding means comprising a pair of scissor grip- ping jaws.
27. In a wrapping machine, means for feeding a wrapper web, means for feeding a tape web, means for superimposing the tape web upon the wrapper web, means for securing the tape web to the wrapper web at spaced points, cutting means for cutting lengths from said superimposed webs, an article conveyor for conveying articles to said lengths, means for wrapping the articles in said lengths, detector means engageable with the articles while on said conveyor, and means controlled by the detector for disabling the web feeding means, the web superimposing means, the web securing means, and the cutting means when an article is not present upon the conveyor, while leaving the wrapping means operative.
28. In a wrapping machine, means for feeding wrappers to a wrapping position, a conveyor for conveying articles to said wrapping position, a detector engageable with articles at a detecting position on the conveyor as the articles approach the wrapping position, wrapping mechanism for wrapping the articles within the wrappers, and means controlled by the detector for disabling the wrapper feeding means when an article is not present upon the conveyor while leaving the wrapping mechanism operative, said detector being adapted to move to a position to block approaching articles when no article is at the detecting position, and means for moving the detector to unblocking position in timed relation to the operation of the wrapping means.
29. In a wrapping machine, end folding mechanism for folding a projecting wrapper against the end of an article, said mechanism comprising a stationary abutment adapted to fold one portion of the wrapper against the article end, a movable abutment adapted to fold a second portion of the wrapper against the article end, and means movable with the movable abutment for moving the wrapper into engagement with the stationary abutment, said movable abutment being movable to a position past the end of the stationary abutment whereby the stationary abutment may be brought into engagement with said second wrapper portion to hold the same upon withdrawal of the movable abutment.
30. In a wrapping machine, end folding mechanism for folding a projecting wrapper against the end of an article, said mechanism comprising a stationary abutment adapted to fold one portion of the wrapper against the article end, a movable abutment adapted to fold a second portion of the wrapper against the article end, and means movable with the movable abutment for

- moving the wrapper into engagement with the stationary abutment, one of said abutments being notched to receive the end of the other abutment whereby said movable abutment may be moved to a position past the end of the stationary abutment to bring the stationary abutment into engagement with said second wrapper portion to hold the same upon withdrawal of the movable abutment.
31. In a wrapping machine, end folding mechanism for folding a projecting wrapper against the end of an article, said mechanism comprising a stationary abutment adapted to fold one portion of the wrapper against the article end, a movable abutment adapted to fold a second portion of the wrapper against the article end, and means on the movable abutment for moving the wrapper into engagement with the stationary abutment, said movable abutment being movable

to a position past the end of the stationary abutment whereby the stationary abutment may be brought into engagement with said second wrapper portion to hold the same upon withdrawal of the movable abutment.

32. In a wrapping machine, a rotary package transfer wheel, arms pivotally mounted on said wheel adapted to engage and move packages from a first position to a second position, wrapper folding means engageable with the packages during movement by said arms, a stationary cam member coaxially mounted with respect to the wheel, and projections on said arms engageable with the cam, and resilient means for urging the projections into engagement with the cam whereby the arms are pivotally moved with respect to the wheel in accordance with the contour of the cam.

MICHAEL J. MILMOE.
